UNITED STATES PATENT OFFICE

2,620,564

CLAMP FOR TELESCOPES OF TRANSITS

Charles O. Rothweiler, Milwaukee, Wis., assignor
to David White Company, Milwaukee, Wis.

Application April 13, 1948, Serial No. 20,781

3 Claims. (Cl. 33—46)

1

My invention relates to clamps and more particularly to an improved clamp for supporting a telescope as part of a transit assembly.

An object of my invention is to provide resiliency in the clamping arrangement, thereby providing positive contact within the adjustable block.

Still another object of my invention is to insure any degree of minute adjustment, due to the resiliency of the stationary block.

A still further object of my invention is to provide a device that is easy to assemble, easy to adjust, variable in its scope and economical to manufacture.

It is manifest that when locking the telescope of a transit into a horizontal position, minute adjustments are imperative for proper spotting operation. It is common practice to slidably move a pair of clamping blocks vertically on a vertical slide to accomplish the correct alignment and clamp the blocks in position on the vertical slide member so that the telescope may be retained in a pre-determined position. With the device illustrated, claimed and specified herein it is possible to adjust the clamping blocks on the vertical slide to permit additional adjustment against the resilient structure, to provide micrometer adjustment of the telescope in a horizontal plane.

Other and further objects of my invention will become more apparent as the description proceeds and when taken in conjunction with the drawings in which

Figure 1 is a side view of the transit head showing the telescope in an angular position disengaged from the retaining blocks which act as clamps.

Figure 2 is a top view of the device as shown in Figure 1.

Figure 3 is an end view of the clamp arrangement taken at the line 3—3 in Figure 1.

Figure 4 is a front view of the clamp arrangement as shown in Figure 3.

Figure 5 is a cross-sectional view of the clamp arrangement taken at line 5—5 in Figure 4, and

Figure 6 is a cross-section of the upper adjustment block taken at the line 6—6 in Figure 5.

Similar characters of reference indicate corresponding parts throughout the several views, and referring now to the same, the character 10 shows a telescope of any conventional design pivotally mounted at 11 within frame members 12 and 12' forming a part of the base 13 which is rotatably mounted on a conventional support assembly shown as 14. The frame member 12 is shown pro-

2

vided with a pair of angular retaining members 15 and 15' pivotally mounted at 16 to the member 12. The retaining members 15 and 15' are equipped with engaging members 17 and lever members 18.

The telescope 10 is shown equipped with a pair of collars 19 having a channel section 20 vertically disposed at the forward face, and a horizontal portion 21 extending outward over and above the channel 20. A threaded adjustment screw 22 engages the portion 21 and is retained by a lock nut member 23 engaging the outwardly extending radial flange 24 on the screw 22. There are shown a pair of clamping blocks 25 and 26 slidably engaging in the groove or channel in the channel section 20 and retained in position by means of screws 27 threadedly engaging the sliding members 28 disposed within the vertical groove.

20 The lower block 26 is provided with a resilient member 29 in the form of a flat spring attached to the one side of the block 26 by means of the screws 30 and extending in an arch across the upper face of the block, and having its depending end 31 suspended without attachment. This will permit resilient clamping action when the engaging member 17 is disposed between the slidably moved block 25 and the fixed block 26 and pressure is exerted upon the members 17 by revolving the screw 22 threadedly engaging the block 25.

25 In operation the blocks 26 are rigidly supported in the channel sections 20 by means of the screws 27 in a position whereby the members 17 of the retaining members 15 and 15' contact the upper arcuate faces of the resilient members 29 mounted on the blocks 26. This will permit adjusting the blocks 25 within the channel sections 20 and by manipulating the screws 22, it will cause the blocks 25 to move vertically against or away from the spring tension of the members 29 for clamping the engaging members 17, which in turn would adjust the horizontal plane of the telescope shown as 10.

30 Obviously, the two sets of clamp blocks on either side of the pivoted mounting 11 of the telescope 10 will permit a very minute adjustment of the telescope 10 and will retain it in any predetermined position.

In the chosen embodiments of my invention there are features not heretofore disclosed in the prior art, and although I have shown a specific structure and particular arrangement of the component parts, I am fully cognizant of the fact that many changes in the form and configuration of the component parts may be made without

affecting their operativeness and without departing from the spirit of my invention or the scope of the appended claims.

Having thus described my invention, what I claim and desire to secure by Letters Patent in the United States is:

1. A device of the character described to be used in combination with a telescope pivotally mounted on a base, said device comprising a collar member engaging the outer periphery of said telescope, said collar member having a vertical face, a channel disposed in said face, and a horizontal portion extending outward from said face at one end of said channel, a pair of clamping members slidably engaging in said channel, one of said clamping members arranged for fastening in said channel in a fixed position and provided with a resilient means attached at one of its ends and extending over the upper face of said clamping member, a screw, said screw mounted in the horizontal portion of said collar member and extending into the other of said clamping members to allow vertical adjustment toward and away from the resilient means over the face of said fixed clamping member.

2. A device of the character described to be used with a telescope pivotally mounted on a base having retaining members disposed therein, said device comprising a collar member engaging the outer periphery of said telescope, said collar member being provided with a vertical channel, and a horizontal member extending above said channel, a pair of clamping elements slidably mounted on the face of said channel, an adjustment screw mounted in the horizontal member, said screw threadedly engaging the upper of said clamping elements, resilient means attached to the lower of said clamping elements and extending across the upper face of the lower of said clamping elements, means for retaining the lower clamping element in a fixed position in said channel, thereby permitting adjustment of said upper clamp element relative to the resilient means on

the lower element when one of said retaining members of said base is disposed between said clamping elements.

3. A device of the character described to be used with a telescope pivotally mounted on a base having retaining members disposed therein, said device comprising a collar member engaging the outer periphery of said telescope, said collar member being provided with a vertical channel, a horizontal member integral with the collar and extending outward above said channel, a pair of clamping elements slidably mounted on the face of said channel, an adjusting screw provided with an outwardly extending flange, said screw being threadedly engaged in the upper of said clamp elements, a retaining member threadedly engaging the horizontal member for contact with the flange on said screw for locking said screw in position, resilient means attached to the lower of said clamping elements and extending across the upper face of the lower of said clamping elements, means for retaining the lower clamping element in a fixed position on said channel, thereby permitting adjustment of said upper clamp element relative to the resilient means of said lower clamping element, when a retaining member of said base is disposed between said clamping elements.
